CLAIM

The ornamental design for a fuel valve plug, as shown and described.

DESCRIPTION

FIG. 1 is a perspective view of the fuel valve plug;
 FIG. 2 is a front elevation view of the fuel valve plug;
 FIG. 3 is a rear elevation view of the fuel valve plug;
 FIG. 4 is a right side elevation view of the fuel valve plug;
 FIG. 5 is a left side elevation view of the fuel valve plug;
 FIG. 6 is a top plan view of the fuel valve plug; and
 FIG. 7 is a bottom plan view of the fuel valve plug.
 The broken lines shown in the drawings are for the purpose
 of illustrating the inner channel portion of the fuel valve plug
 that forms no part of the claimed design.
